CLAIM

The ornamental design for a front combination lamp of automobiles, as shown and described.

DESCRIPTION

FIG. 1 is a front perspective view of the front combination lamp of an automobile showing my new design, with the broken line showing for illustrative purposes and forming no part of the claimed design.

FIG. 2 is a front perspective view thereof.

FIG. 3 is a plan perspective view thereof; and,

FIG. 4 is a right side perspective view thereof.
